CLAIM

We claim the ornamental design for a door controller, as shown and described.

DESCRIPTION

FIG. 1 is a top, front, right perspective view of a door controller;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The portions of the door controller shown in broken lines disclose environmental structure and form no part of the claimed design.
